AIR WASHER

Application filed October 9, 1929. Serial No. 398,531.

It is well known to those skilled in the art that the most effective way of washing air is to provide wet surfaces over which the air is caused to pass. Heretofore, such washers have been made of stationary scrubber plates which were kept wet by spray roses or water jets. The disadvantages of such a stationary arranged washer is that numerous nozzles or spray roses with much extra equipment in the nature of piping must be provided, and the minute orifices of the spray roses or jets become easily clogged, requiring repairs with attendant interruption of operation. Moreover, such stationary washers require considerable space, as well as a relatively great quantity of water to keep their surfaces wet. Furthermore, such devices require pumps and outside mechanism to keep the liquid in circulation.

It has been an object of my invention to overcome the disadvantages above pointed out, by providing a washer having scrubber plates mounted upon a rotating drum and dipping into a water pan, thereby occupying but relative small space and eliminating the elements which usually cause trouble.

Another object has been to provide a scrubber plate having means for maintaining the surfaces of the plate in a wet condition while they are being rotated from the point where they leave the surface of the water to a point where they are again emersed therein.

Moreover, my device is of such a nature that the air being treated, in passing through the drum, causes the drum to rotate, without the use of any outside means.

Moreover, in my device no water circulating means are necessary since the scrubber plates are moistened by dipping into the water.

Furthermore, my device is of such a nature that the air is caused to pass twice through the scrubber plates, thus greatly increasing the efficiency of the device.

The above objects and advantages have been accomplished by the device shown in the accompanying drawings, of which:

Fig. 1 shows a side, sectional elevation of my complete device.

Fig. 2 is a fragmentary, sectional view, taken on line 2—2 of Fig. 1.

Fig. 3 is an enlarged, fragmentary, sectional view of one of the scrubber plates.

Fig. 4 is a similar view of a modified form of scrubber plate.

My device is designed primarily to wash air that is drawn through a heating unit. Such a heating unit is shown in Fig. 1 at 5, and comprises a suitable heating coil 6, through which steam is passed, and a blower 7 which takes air out of the casing 5 through an inlet 8 formed at each side thereof, into the fan casing 9, thence upwardly in the direction of the dotted arrows and through an outlet 10 which projects it into the room being heated. My device is preferably placed below such a heating unit, as shown in Fig. 1, and comprises a casing 15. The casing may have a solid back wall 16 and an opening 17 formed in its front wall 18. The opening 17 provides an inlet for the air. The wall 18 extends upwardly, thus forming the front of a water tank 19. The height of the wall 18 is preferably somewhat greater than the depth of water contained in the trough. Obviously, if desired, instead of the tank formed by the casing, a separate water pan may be used.

A washer drum 20 is mounted within the casing 15 and is supported by suitable bearings 21 in which the shaft 22 of the drum rotates. The drum is preferably provided with an end plate 23 at each end thereof to which are secured the ends of the scrubber plates 24. Each of these scrubber plates extends from end to end of the drum, and each has its longitudinal sides 25 and 26 bent at any suitable angle to each other with the inner apex 27 facing the direction of flow of the air entering the drum, whereby the scrubber plates form buckets or vanes for the air, so that its contact with such buckets or vanes cause the drum to rotate. The side 25 of each scrubber plate is provided with a scupper 28, and the side 26 is provided with a scupper 29. The scupper 28 is formed by a flange 30 which is arranged so that it occupies a position in respect to the side 25 which is in front of this side when the drum is rotating, and

the scupper 29 is formed by a flange 31 which is so arranged that it occupies a position in respect to the side 26 which is behind this side when the drum is rotating.

A division plate 35 is arranged above the drum and preferably extends forwardly to the front side of the casing at the top of the opening 17, whereby the air will be directed downwardly and caused to pass through the scrubber plates of the drum which are exposed to the opening.

It will be obvious from the foregoing that when the fan 7 is being operated, air will be drawn in through the inlet opening 17 of my device and will be impinged against the trough-shaped scrubber plates 24 and cause the drum to rotate in the direction of the arrow. After the drum is caused to rotate, the scrubber plates will be drawn through the water contained in the tank 19, which will cause their surfaces to be wet and also cause the scuppers 28 and 29 to be filled with water. The velocity of the incoming air striking against the side 26 of the plate will serve to retain the water within the scupper 29. The air will be deflected between the surfaces of the adjacent plates and caused to enter the center of the drum. After the drum is rotated and the side 25 of the scrubber plate reaches a horizontal plane, the water which is held by the scupper 28 carried by this side will be spilled over the outside surface of this side of the scrubber plate and also over the outside surface of the side 26 thereof, thus wetting such surfaces. The air after having entered the center of the drum is caused to move to the opposite side of the drum where it again passes through the scrubber plates. Obviously, the air in coming in contact with the wet surfaces of the plates is cleaned, such cleaning being more efficient because of the double passage of the air through the drum. When the plates are rotated still farther, the water carried by the scupper 29 is spilled over the inner surface of the plate, thereby also maintaining this surface in a wet condition.

In some cases, it might be that the air passing through the scrubber plates will carry with it drops of water from the underside of the side 26 of the scrubber plates, and at the outer edges thereof. In many cases such drops of water would be carried up with the air and be deposited on the heated surfaces, thereby impairing the heating efficiency of such surfaces. In order to avoid the possibility of such entrained water, I have provided an auxiliary scupper 36 attached to the side 25 of each scrubber plate at a point opposite the scupper 28, as shown in Fig. 4. It will be seen that any solid particles of water which would be carried up along the inner surface of the side 25 will be caught by the auxiliary scupper 36 and prevented from leaving the edge of the scrubber plate. This scupper is preferably in the form of a U-

shaped section which is welded or otherwise secured to the side 25 of the scrubber plate.

While I have referred to water as the liquid for wetting the plates, it is obvious that oil or any other liquid suitable for cleaning purposes may be used. In cases where the liquid used is so viscous that the passage of air through the device will not create sufficient power to rotate the drum, it may be necessary to provide some suitable means of positively driving the drum, which may be in the nature of any well known and common form of motive power or connection to the motor which drives the wheel of the fan. Furthermore, while I have shown the side 25 of the scrubber plate as being provided with a scupper 28 formed by a forwardly turned flange 30, and the side 26 as being provided with a scupper formed with a rearwardly turned flange 31, it is obvious that these flanges may be turned in a number of various directions and somewhat the same results obtained. However, I have found that the arrangement of scuppers shown in Fig. 3 to be the most efficient.

These and other modifications of the details herein shown and described may be made without departing from the spirit of my invention or the scope of the appended claims, and I do not, therefore, wish to be limited to the exact embodiment herein shown and described, the form shown being merely a preferred embodiment thereof.

In the appended claims where I refer to the washer drum of my device, I mean a drum having scrubber plates which extend from end to end of the drum, the drum thus being uniform in cross-section throughout its length, as shown in the drawings.

Having thus described my invention, what I claim is:

1. An air washer, comprising a casing, a washer drum rotatably mounted within the casing, a plurality of scrubber plates carried by the drum, each plate having a scupper formed at each of its longitudinal edges, each of the plates being formed with two longitudinal sides bent at an angle to each other and having the inner or trough-shaped surface facing the inlet of the device, whereby the air currents passing into and through the device will cause the drum to be rotated.

2. An air washer, comprising a casing, a washer drum rotatably mounted within the casing, and a plurality of scrubber plates carried by the drum, each scrubber plate having two longitudinal sides bent at an angle to each other, the side located toward the periphery of the drum having a scupper formed by a flange bent forwardly and in advance of the side in the direction of rotation, the side of the plate toward the center of the drum having a scupper formed by a rearwardly turned flange which is behind this side of the plate when the drum is in rotation.

3. An air washer comprising a casing, a washer drum rotatably mounted in the casing, and a plurality of scrubber plates carried by the drum, each scrubber plate being im-
5 perforate and of trough-shape formation and having its inner trough-shaped face facing the air inlet of the device, whereby the air currents, striking the trough-shaped faces of the scrubber plates, will cause the drum to rotate.
- 10 4. An air washer comprising a casing, a washer drum rotatably mounted in the casing, a plurality of scrubber plates carried by the drum, and a scupper formed at each longitudinal edge of each scrubber plate, each
15 scrubber plate being of trough-shape formation and having its inner trough-shaped face facing the air inlet of the device, whereby the air currents, striking the trough-shaped faces of the scrubber plates, will cause the drum
20 to rotate.
5. An air washer comprising a casing having an air inlet and an air outlet, a water pan arranged in the bottom of the casing, a washer drum rotatably mounted within the casing,
25 a plurality of trough-shaped scrubber plates carried by the drum and located so as to dip into the pan, and an auxiliary scupper provided at the outer edge and at the trailing side of each of the scrubber plates, whereby
30 air passing over the wet surfaces of the scrubber plates will be washed and entrained water will be collected by the auxiliary scuppers.
6. An air washer comprising a casing having an air inlet and an air outlet, a water pan arranged in the bottom of the casing, a washer drum rotatably mounted within the casing,
35 a plurality of trough-shaped scrubber plates carried by the drum and located so as to dip into the pan, each longitudinal edge of each
40 of the plates being provided with a scupper, and an auxiliary scupper provided at the outer edge and at the trailing side of each of the scrubber plates, whereby air passing over the wet surfaces of the scrubber plates will
45 be washed and entrained water will be collected by the auxiliary scuppers.
7. An air washer comprising a casing, a water pan located at the bottom of the casing, a rotatably mounted, hollow, washer drum
50 carried by the casing and so located so that it will dip into water contained in the pan, a partition arranged above the drum, and means carried by the drum for causing it to be rotated, whereby air will pass into the
55 drum at the inlet side of the partition and be passed out of the drum and into the casing at the outlet side of the partition.
8. An air washer comprising a casing, a water pan located at the bottom of the casing,
60 a rotatably mounted, hollow, washer drum carried by the casing and so located so that it will dip into water contained in the pan, a plurality of trough-shaped scrubber plates carried by the drum, a partition arranged
65 above the drum, and means carried by the
- drum for causing it to be rotated, whereby air will pass into the drum at the inlet side of the partition and be passed out of the drum and into the casing at the outlet side of the partition.
- In testimony whereof, I have hereunto signed my name.
- CHARLES C. CHEYNEY.
